UNITED STATES PATENT OFFICE.

HENRY BICKFORD, OF CINCINNATI, OHIO.

FEED DEVICE FOR DRILLING-MACHINES.

SPECIFICATION forming part of Letters Patent No. 237,722, dated February 15, 1881.

Application filed September 15, 1880. (No model.)

To all whom it may concern:

Be it known that I, HENRY BICKFORD, of Cincinnati, Ohio, have invented a new and useful Improvement on Drilling-Machines, of 5 which the following is a specification.

My invention relates to feeding devices for drilling mechanism; and it consists in a new and useful quick-return mechanism to be used in connection with the ordinary feed device, as 10 will be hereinafter more fully specified and definitely claimed.

In the accompanying drawings, Figure 1 is a vertical elevation of a drilling-machine with 15 my improved quick-return mechanism shown as attached to a well-known feeding device. Fig. 2 is a perspective view of the feeding device of a drilling-machine with my improved quick return attached thereto; and Fig. 3 is a longitudinal sectional view of the mechanism 20 used for feeding or for quick return.

Letters of like character in each of the figures represent corresponding parts of the machine.

The customary drill-spindle A and rack B, 25 with its pinion C, are attached to and driven by a disk, E, by means of shaft d. When it is desired to feed rapidly or to have a quick return of the drill, the disk E is rotated by a lever, f, by which means the drill-spindle may 30 be elevated or depressed while the gradual feed mechanism remains stationary. This is accomplished by tilting the lever f into the position represented by dotted lines f', which

causes a projecting piece, c', forming part of lever f, to be withdrawn from the evenly-divided circumferential cavities c formed in the face of the worm-wheel D. The worm-wheel D then being loose upon shaft d remains detached until the projection c' of lever f again engages in the cavities c. Then the whole feeding mechanism is again connected and may be rotated by hand-wheel F.

The lever f is pivoted through the center of disk E by pin i, and the end upon which the projection c' is formed is provided with a cone-pointed pin, a, which is forced, by a spring beneath it, into a corresponding cone-shaped receptacle formed in cap m of disk E, and the projection c' of lever f engages with cavities c of worm-wheel D, and is thus kept in position until purposely forced out.

Having thus described my invention, what I claim as new, and desire to secure by Letters Patent, is—

In a drilling-machine, the disk E, with pivoted lever f, having a projection, c', constructed to engage with cavities c in disk E, in combination with the customary feeding mechanism of a drilling-machine, as and for the purpose specified.

In testimony whereof I have hereunto set my hand.

HENRY BICKFORD.
